(57) **CLAIM**

The ornamental design of a housing for a power outlet, as shown and described.

DESCRIPTION

FIG. 1 is a front perspective view of a first embodiment of a housing for a power outlet showing my new design; FIG. 2 is a rear perspective thereof; FIG. 3 is a front elevational view thereof; FIG. 4 is a rear elevational view thereof; FIG. 5 is a top plan view thereof; FIG. 6 is a bottom plan view thereof; FIG. 7 is a left elevational view thereof; FIG. 8 is a right elevational view thereof; FIG. 9 is a front perspective view of a second embodiment of a housing for power outlet showing my new design; FIG. 10 is a rear perspective view thereof; FIG. 11 is a front elevational view thereof; FIG. 12 is a rear elevational view thereof; FIG. 13 is a top plan view thereof; FIG. 14 is a bottom plan view thereof; FIG. 15 is a left elevational view thereof; and, FIG. 16 is a right elevational view thereof.

The broken lines shown in the drawings are included for the purpose of illustrating unclaimed portions of the housing for a power outlet and form no part of the claimed design.

1 Claim, 8 Drawing Sheets
